ATTORNEY

UNITED STATES PATENT OFFICE

LEON PERRON, OF BROOKLYN, NEW YORK

INVALID CHAIR AND CABINET

Application filed October 20, 1931. Serial No. 570,011.

This invention relates to an improvement in chairs, and particularly to an improved combined invalid chair and cabinet, the object to provide a desirable chair structure and a cabinet associated therewith to conveniently carry medicine or other articles to be used by the invalid.

Another object of the invention is to provide a chair for tuberculosis patients, or other patients, on which the arms and back are so positioned and arranged so as to protect the body of the person using the chair while exposing the person to free contact with the air.

An additional object is to provide an invalid chair which is formed with rollers and with the seat arrangement swiveled on a support so that the person using the chair may readily move the chair from place to place and may swing the seat around to face in any desired direction.

An additional object is to provide a combined invalid chair and cabinet wherein the back structure is formed to provide a cabinet for the reception of articles desirable for the person using the seat, and a canopy formed with a bow acting at one time to maintain the canopy taut, and at another time acting to lock the door of the cabinet against opening.

In the accompanying drawing—

Figure 1 is a perspective view of the combined invalid chair and cabinet disclosing an embodiment of the invention.

Figure 2 is a longitudinal vertical sectional view through the chair shown in Figure 1.

Referring to the accompanying drawing by numbers, 1 indicates a support, and 2 the seat body which merges into a back 3 forming part of the cabinet 4. The support 1 is preferably formed with a base 5 of wood or other material connected in any desirable way with the side members 6, and suitably braced by the respective bracing members 7. Each of the side members 6 are preferably provided with a connecting bar 8 merging into the outwardly extending bifurcated members 9, each bifurcated member 9 accommodating a comparatively small wheel 10 connected to the bifurcated member by an

axle or pin 11. Preferably, this stiff arrangement of bifurcated members, as described, is used as it permits the chair to be wheeled from place to place readily without permitting the chair to move in all directions as would be the case if casters were used. The base 5 is provided with a threaded sleeve 12 accommodating the threaded shaft 13 which is rigidly secured to metal base plate 14, which plate in turn is rigidly secured to the seat 2 by screws or other means. It will be noted that the seat 2 is provided with a pad 15, and the back 3 is also provided with a pad 16. Connected with the seat 2 and the back 3 are what may be termed arms 17 and 18 and wind-shields 19 and 20. When an invalid, as for instance a tuberculosis patient, is using the chair, the entire body will be protected against the blast of wind passing the chair but the patient will be exposed to the air and get the benefit thereof without being subjected to the disagreeable feature of the wind blowing directly on the body. Of course, if the patient desires some of the wind or breeze to strike the body, a slight forward bending of the upper part of the body will expose the face and other parts to the wind.

In many of the tuberculosis camps and hospitals, patients must sit out-of-doors exposed to all kinds of weather in order to get the benefit of the air. While this exposure to the air is essential, it is not necessary to expose the patients to the disagreeable action of heavy winds or to slight snow storms which is now the case. By providing the members 17 to 20 inclusive, the patient is exposed to the air but protected somewhat against the wind and snow storms. The canopy 21 also acts to protect the patients against rain and snow storms, and this canopy may be of any desired material, as for instance, a good grade of duck secured by tacks, adhesive, or otherwise, to the frame 22 of the cabinet 4. The front edge of the canopy is connected by screws or other means 23 to the cross bar 24 of the bow 25. This bow is pivotally mounted at 26 on the wind-shields 19 and 20, and when the parts are formed as shown in Figure 1, the patient is

protected against snow or rain which may come down almost in a vertical direction. When it is desired to expose the patient to the sun, the canopy is thrown back, as illustrated in Figure 2. This not only disposes of the canopy as far as protection is concerned, but the bow 25 acts as a lock for maintaining the door 27 of the cabinet 4 closed. This door may be of any desired kind and held in place by suitable hinges and catch, but when it is desired to positively lock the door against opening, the bow 25 is shifted to the position shown in Figure 2. It is usually moved to this position when the chair is to be shifted or moved a considerable distance. In this way any medicine or other articles in the cabinet 4 will be protected against loss by the accidental opening of the door.

In tuberculosis camps and elsewhere where patients are to be exposed to the air out-of-doors, heretofore it has been necessary for the nurse to come out and give the patients their medicine from time to time, or for the patients to get up and go into the house to secure their medicine. By having the medicine in cabinet 4, the patient, if far enough advanced, may secure his own medicine, or, if desired, the nurse can go out and administer the medicine.

At the front of the seat 2 a U-shaped bar 28 is secured by suitable screws 29, said bar having the respective legs thereof extend through the fittings 30, each fitting carrying a set screw 31 which is adapted to be tightened, so that the foot rest 32, which is rigidly secured to the fittings 30, may be supported at any desired elevation. Preferably, the foot rest is divided into two parts and connected together by suitable hinges 33.

While the chair has been described more particularly for the use of tuberculosis patients in camps and elsewhere, it is, of course, understood that it could be used in hospitals anywhere, and in fact, in many other places without departing from the spirit of the invention.

I claim:

1. A combined invalid chair and cabinet comprising a support, a seat structure mounted on the support and merging into a back, means co-acting with the back for producing an article receiving cabinet, a canopy adapted to extend over the upper part of the chair when in one position, a bow pivotally connected with the upper part of the chair and also connected with the canopy for maintaining the canopy taut when the bow is in one position, said bow being adapted to be swung to the rear so as to overlap part of the cabinet for locking the same closed.

2. A combined invalid chair and cabinet comprising a base, a seat mounted on the base, said seat merging into a back, means including a door co-acting with the back for producing a cabinet, a swinging U-shaped

member, when in one position acting to overlap and lock the door against opening, and a canopy connected with said U-shaped member, said canopy being held taut by the U-shaped member when the U-shaped member is swung to a second position.
